UNITED STATES PATENT OFFICE.

FRANCIS H. BUZZACOTT, OF CHICAGO, ILLINOIS.

DESIGN FOR A CAMP-STOVE.

SPECIFICATION forming part of Design No. 33,232, dated September 18, 1900.

Application filed July 26, 1900. Serial No. 24,820. Term of patent 3½ years.

To all whom it may concern:

Be it known that I, FRANCIS H. BUZZACOTT, a citizen of the United States, residing at Chicago, in the county of Cook and State of Illinois, have invented and produced a new and original Design for Camp-Stoves, of which the following is a specification, reference being had to the accompanying drawing, forming part thereof.

- 10 As shown in the drawing, the leading or material feature of my design consists of a rectangular oblong box-shaped structure A, having three plates a b c, forming the top, each provided with a rectangular opening.
- 15 On opposite ends, only one of which is shown, are handles d d. On one end above the center is an opening e, at the sides and bottom of which are flanges. In the same end at opposite sides close to the bottom are openings f.
- 20 The side of the structure which is presented to view is provided with the paneled doors g

and h, supported at their lower ends in loops l l' l'' and provided at their upper ends with hand-sockets g' h', and a bar k is shown extending lengthwise across the doors and resting at its opposite ends in loops i i' near the opposite ends of said side.

The form of damper employed is represented at m.

Having described my invention, what I claim as new, and desire to secure by Letters Patent, is—

The design for a camp-stove as herein shown and described.

In testimony whereof I have signed my name in the presence of two subscribing witnesses.

FRANCIS H. BUZZACOTT.
